[57] CLAIM

The ornamental design for a tire, as shown and described.

DESCRIPTION

FIG. 1 is a perspective view of a tire showing our new tread design, it being understood that the tread pattern is repeated uniformly throughout the circumference of the tire and that the opposite side is substantially the same as that shown;

FIG. 2 is an enlarged fragmentary front view thereof; and,

FIGS. 3-4 are enlarged fragmentary front views of a second and third embodiment of a tire, it being understood that the tread pattern of these embodiments is repeated uniformly throughout the circumference of the tire as in the FIG. 1 illustration, and that the sides are substantially the same as the first embodiment shown in FIG. 1.
